UNITED STATES PATENT OFFICE.

ALDEN L. PUTNAM, OF DETROIT, MICHIGAN, ASSIGNOR TO DETROIT PRESSED STEEL COMPANY, OF WILMINGTON, DELAWARE, A CORPORATION OF DELAWARE.

DESIGN FOR A VEHICLE-WHEEL DISK.

57,264.

Specification for Design.

Patented Mar. 8, 1921.

Application filed July 28, 1920. Serial No. 399,613. Term of patent 14 years.

To all whom it may concern:

Be it known that I, ALDEN L. PUTNAM, a citizen of the United States of America, residing at Detroit, in the county of Wayne and State of Michigan, have invented a certain new, original, and ornamental Design for a Vehicle-Wheel Disk, of which the following is a specification, reference being had therein to the accompanying drawings, forming part thereof, in which—

Figure 1 is a perspective view of the disk.

viewed from one side thereof; Fig. 2 is a similar view, viewed from another side thereof; and Fig. 3 is a cross-section.

I claim:

The ornamental design for a vehicle wheel disk, substantially as shown.

In testimony whereof I affix my signature.

ALDEN L. PUTNAM.
